UNITED STATES PATENT OFFICE.

HAROLD A. DOUGLAS, OF GRAND RAPIDS, MICHIGAN, ASSIGNOR TO PETER C. BURNS, OF CHICAGO, ILLINOIS.

TELEPHONE-SWITCHBOARD.

SPECIFICATION forming part of Letters Patent No. 674,402, dated May 21, 1901.

Application filed November 2, 1898. Serial No. 695,273. (No model.)

To all whom it may concern:

Be it known that I, HAROLD A. DOUGLAS, a citizen of the United States, residing at Grand Rapids, in the county of Kent and State of Michigan, have invented a certain new and useful Improvement in Telephone-Switchboards, of which the following is a specification.

My invention relates to certain improvements in telephone-switchboards known as "transfer" or "trunking-board" systems.

At the central exchange of a telephone system a switchboard is employed for the purpose of temporarily connecting together a multiplicity of subscribers' lines, whereby conversation may be carried on between any two subscribers of the system. A comparatively small number of subscribers may be connected and disconnected with facility on a small board; but as the number of subscribers increases, necessitating the employment of operators located at remote points from each other in front of the switchboard, the problem of connecting and disconnecting becomes complicated and difficult. Two systems are now more generally used, known, respectively, as the "trunking-board" system and the "multiple-board" system. In the latter the switchboard is divided into sections and the lines of all the subscribers are provided with means for interconnection on each of the sections, whereby an operator at any one of the sections may make connection between any two lines of the entire system. In the former or trunking-board system the lines of the subscribers are divided into groups, each of which groups are terminated upon the respective sections. In such a system an operator at a given section may establish a connection between two lines grouped upon that section; but to make connection with a line of the group of that section and a line of a group terminating at another section it becomes necessary to provide means for signaling and communication between the two sections in order that the two operators may coöperate with one another to establish the desired connection—in some cases what are called the "trunking-section" and "trunking operator." The lines which may be connected by any one opera-

tor on her section without the intervention of any other operator are termed "local" lines, while lines which terminate in other sections requiring the coöperation of two operators in relation to the local lines are termed "foreign" lines.

The object of my invention is to provide a positive means of signaling between the operators, whereby the operator at the foreign or distant section or groups may be signaled by the local operator, and in accomplishing this result to provide means whereby the act of making or breaking the connection at the local sections gives a signal at the trunking or foreign section, which signal is withdrawn as the operator at the trunking or foreign section proceeds to make a connection and which signal is again given should the trunking or transfer operator proceed to disconnect when the line is still in use.

My invention has certain other objects in view; and it consists in certain features about to be described, reference being now had to the accompanying drawings, in which—

Figure 1 is a diagrammatic view of the circuit arrangement. Fig. 2 is a face view of a portion of switchboard embodying my improvements. Fig. 3 is a side view of the trunking or foreign section. Fig. 3^a is a horizontal section of a portion of the same. Fig. 4 is a detail view of the transfer-jack. Fig. 5 is a detail perspective view showing the manner of effecting contact. Fig. 6 is a view of the transfer-jack and the transfer-plug inserted therein. Fig. 7 is an elevation of a portion of the foreign section of the board, showing the seat or socket for the foreign transfer-plug. Figs. 8 and 9 are vertical sections of the same, the former without the plug and the latter with the plug inserted. Fig. 10 is a horizontal section taken on line 10-10 in Fig. 7.

The subscribers' stations are designated at A and A², the station A being the calling and station A² the called subscriber. The lines 1 and 2 of the calling-station are led to the spring-jack B on the switchboard after passing through the calling-annunciator B². These instrumentalities are of the ordinary construction. The plug B³ of the subscriber's jack B is connected through the operator's listening

and ringing key B^4 , this construction and arrangement being of the usual character. The clearing-out drop B^5 is included, as is usual, in the cord-circuit of the plug B^3 .

5 Assuming that it is desired to establish a connection between the circuits of two different groups of subscribers' lines—as, for instance, between the circuits of stations A and A^2 , terminating on different sections—the 10 operator inserts the plug D in the transfer-jack E. It comprises a battery spring-strip e , which is normally in contact with the transfer or signaling circuit controlling spring-strip f . The other battery spring-strip, h , is 15 normally out of contact. The line-spring j is connected to the limb 3 of the trunking circuit, the other limb, 4, of which is connected to the frame of the jack. At the trunking-section a signaling instrumentality is provided, in this instance the incandescent lamp H, included in the line 5, connected with the controlling-spring f of the jack E. This line 5 is also connected to the circuit-controlling spring J of the transfer-plug seat 20 K in series with the lamp H.

25 The transfer-plug seat K comprises a plug-socket k and the controlling-spring J and the battery-spring m . The controlling-spring J is normally in contact with the battery-spring m when the plug is in the socket k . The battery L is connected by the common battery-leads 6 and 7, with the battery-springs e and h of the jack E, and also with the battery-spring m and the frame of the plug-seat K 30 by the limbs 8 and 9, connected to the leads 6 and 7.

The transfer-plug is designated M.

35 The transfer order-circuit is connected in the ordinary and usual manner, my invention residing in the means of effecting transfer-signals.

40 The operation of my device is as follows: When the plug D, corresponding to the other plug, B^3 , of the pair and inserted in the switch-board-jack, is inserted in the transfer-jack E, the normal contact of the controlling-spring f with the battery-spring e is broken and a contact made between battery-spring h and the controlling-spring f , and as the transfer-plug M at the transfer-section is now in its 45 socket k the circuit is closed through battery L as follows: from battery-spring h of jack E, through common battery-lead 6, battery L, branch 8, to controlling-spring j of plug-socket k , through the lamp H and return-lead 5 to spring f of jack E. Thus the lamp H is 50 excited by battery L to display a signal. This lamp-signal informs the operator from what section the call is extended, as it displays the 55 number of the trunk-line over which the connection is to be made. The transfer operator is then notified in the usual manner over the common order-circuit of the number of that subscriber's line with which connection is 60 desired. She thereupon removes the transfer-plug M of the trunk-circuit over which the signal is extended—in this instance, as shown,

65 the circuit-leads 3 and 4—and then inserts the said plug in the subscriber's jack of the called-subscriber's line—in this instance the jack M^2 of the subscriber A^2 . The removal of the plug M breaks the contact between controlling-spring J of plug-seat K and the battery-spring m , thus opening the common battery-circuit and cutting out the battery L, 70 thereby extinguishing the lamp H and withdrawing the signal. As the cords of the plug M are connected with the leads 3 and 4 and springs J and frame of jack E, as shown, the conversation may be carried on over the established circuit between the subscribers' stations A and A^2 . When the subscriber's answering operator is notified by means of clearing-out drop B^5 in the usual way that conversation is completed, she withdraws the 75 plug D from the transfer-jack E, restoring the normal connection between controlling-spring f and the battery-spring e , thereby closing the common battery-circuit through common battery-lead 7, battery L, branch 9, 80 controlling-spring J of plug-seat K, lamp H, and return-wire 5. The lamp is then excited to display a signal, and as the connection is established this is a notification to the transfer operator to disconnect, which is accomplished by removing the plug M and replacing it in the plug-socket k of the plug-seat K. 85

90 Should the transfer operator by mistake remove the plug M while the connection is still in use by the subscribers, the lamp H will be excited to display a signal notifying the operator of her error. This results because the controlling-spring J of plug-seat K contacts with battery-spring m , as the plug M when withdrawn automatically reseats in 95 plug-socket k , the connections being the same as hereinbefore described.

99 It will be observed that when the lamp H is lighted to attract the attention of the operator at the transfer-board to make a connection the plug D of the main board is in position within the trunking-jack E thereof and the transfer-plug M is in position within the plug-seat K of the transfer-board, and also that when the lamp is lighted for the purpose 105 of having the transfer operator disconnect established connections both of these plugs are out of their respective jacks. It will be further observed that in the normal condition 110 of the apparatus, either before a connection with the transfer-board has been made or after one has been broken, the main-board trunking-plug D is out of its jack E, while the transfer trunking-plug M is in position within its seat K, and also that during the 115 establishment of a connection the plug D is in position within its jack E, while the plug M is out of its seat K. In other words, the lamp H is lighted when the trunking-plug D is in position in its jack, and the plug M in 120 position in its seat and also when said plugs are out of said jack and off said seat, respectively; but said lamp is not lighted when either the plug D is in its jack and the plug 125

M off from its seat or the plug D out of its jack and the plug M on its seat. It will thus be seen that the connection of the battery L with the jack E and the seat K is such as 5 to include the lamp H in the battery-circuit when the plug D is in its jack and the plug M on its seat and also when the plug D is out of its jack and the plug M off from its seat and to cut said lamp out of such circuit when 10 either the plug D is in its jack and the plug M off from its seat, or vice versa.

Having thus described my invention, what I claim as new therein, and desire to secure by Letters Patent, is—

15 1. In a telephone system, the combination with a main switchboard and a transfer-board, of a transfer spring-jack on said main board and a plug-seat on said transfer-board, a trunk-circuit extending between said boards 20 and terminating at the main board in said spring-jack, a connecting-plug for the other or transfer end of said trunk-circuit normally seated within said seat, an operator's connective means at the main board including a 25 connecting-plug, a signaling device associated with said seat, a generator to operate said device; and circuit connections from said generator and device to the said jack and seat for operating the device when an operator's 30 plug is in the jack and the trunk-plug is in its seat and also when the trunk-plug is out of its seat and the operator's plug is withdrawn from the jack.

2. In a telephone system, the combination 35 with a main switchboard and a transfer-board, of a transfer spring-jack on said main board and a plug-seat on said transfer-board, a trunk-circuit extending between said boards and terminating at the main board in said 40 spring-jack, a connecting-plug for the other or transfer end of said trunk-circuit normally seated within said seat, an operator's connective means at the main board including a connecting-plug, a signaling device associated 45 with said seat, a generator to operate said device; and circuit connections from said generator and device to the said jack and seat for rendering the said device operative when an operator's plug is in the jack and 50 the plug is in its seat and also when the trunk-plug is out of its seat and the operator's plug is withdrawn from the jack, and for rendering the same inoperative at all other times.

55 3. In a telephone system, the combination with a main switchboard and a transfer-board, of a transfer spring-jack on said main board and a plug-seat on said transfer-board, a trunk-circuit extending between said boards 60 and terminating at the main board in said spring-jack, a connecting-plug for the other

or transfer end of said trunk-circuit normally seated within said seat, an operator's connective means at the main board including a connecting-plug, a signaling device associated 65 with said seat, a generator to operate said device; circuit connections for said generator and device to said jack and seat comprising a conductor from each pole of the generator to the said jack and seat, another conductor 70 from the jack to the seat including the said signaling device; and contacts in the said jack and seat normally connecting said signaling-conductor with the same pole of the generator, and for disconnecting it therefrom 75 and connecting the other pole thereto when an operator's plug is in the jack or the trunk-plug is removed from its seat.

4. In a telephone system, the combination with a main switchboard and a transfer-board, 80 of a transfer spring-jack on said main board and a plug-seat on said transfer-board, a trunk-circuit extending between said boards and terminating at the main board in said spring-jack, a connecting-plug for the other 85 or transfer end of said trunk-circuit normally seated within said seat, an operator's connective means at the main board including a connecting-plug, a signaling device associated 90 with said seat, a generator to operate said device; contacts in the jack and seat connected with each side of the generator, another contact in the jack and also in the seat and operatively connected with the signaling device and normally in contact with the same 95 side of the generator, said latter contacts being disconnected therefrom and thrown into contact with the other side of the generator when an operator's plug is in the jack or the trunk-plug is removed from its seat. 100

5. In a telephone system, the combination with a main board and a transfer-board, trunk-circuits therebetween, a signaling device for each trunk at the transfer-board, a generator, signaling-circuits extending between the two boards comprising a common conductor including the said device, and conductors from each side of the generator, the said common conductor being normally connected at the two boards with a conductor 105 from the same pole of the generator and means to throw said common conductor into contact with the conductor from the other pole in initiating and completing connections through the trunk. 110

In testimony whereof I affix my signature in presence of two witnesses.

HAROLD A. DOUGLAS.
